(57) **CLAIM**

The ornamental design for a shoe sole insert, as shown and described.

DESCRIPTION

FIG. 1 is an exploded top perspective view of a shoe sole insert, showing our new design.

FIG. 2 is a top perspective view thereof, shown in assembled condition.

FIG. 3 is a top perspective view thereof, shown in environmental use condition; and,

FIG. 4 is another top perspective view thereof, shown in use condition.

The broken line portions of FIG. 3 are included to show unclaimed subject matter only and form no part of the claimed design.
